UNITED STATES PATENT OFFICE.

JOHN F. RUDD, OF KANSAS CITY, MISSOURI, ASSIGNOR TO CLARENCE E. MEAD, OF CHICAGO, ILLINOIS.

PNEUMATIC CARPET-CLEANING MACHINE.

No. 906,165.

Specification of Letters Patent.

Patented Dec. 8, 1908.

Application filed March 22, 1907. Serial No. 363,989.

To all whom it may concern:

Be it known that I, JOHN F. RUDD, a citizen of the United States, residing at Kansas City, in the county of Jackson and State of Missouri, have invented certain new and useful Improvements in Pneumatic Carpet-Cleaning Machines, of which the following is a specification.

This invention relates to the construction 10 of a carpet cleaning machine by which the dust and dirt will be positively and effectively removed from the carpet and transmitted to a stream of water, so that the dust and dirt will be assembled by the water and 15 not escape into the room and atmosphere, thereby preventing injurious effects to the operator of the machine from inhaling the dust and dirt.

The objects of the invention are to construct 20 a support over which the carpet is made to travel so as to be contacted by a plurality of revolving brushes, which engage the nap of the carpet and operate to separate and remove the dust and dirt; to employ 25 a plurality of supporting feed rollers and a plurality of rotary brushes, with the brushes interposed between the feed rollers, and having a more rapid revolution than the feed rollers, allowing the feed rollers to 30 serve as means for holding back the forward travel of the carpet; to locate each 35 rotary brush in the upper end of a hydro-pneumatic tube, operating under suction to draw down and remove the dust and dirt, separated or dislodged from the carpet by the operation of the revolving brush; to produce 40 a suction in the upper or air section of the hydro-pneumatic tube by means of a stream of water, flowing downwardly in the lower or water section of the tube, the two sections being connected and forming 45 a continuous hydro-pneumatic tube; to furnish a tank for holding water, having communication with the lower or water section of the tube, and supplying water to the tank, so as to maintain a continuous flow through 50 the lower or water section of the tube, and thereby maintain the suction in the upper or air section of the tube; to discharge the water from a plurality of tubes into a common 55 receptacle for return to a force pump, so as to maintain a continuous circulation of water, until the water becomes so impregnated with dust and dirt as to be nonusable; to automatically open and close the upper or

air section of each tube by means of a valve actuated by the forward travel of the carpet or otherwise; to control the flow of water from the tank into the lower or water section of each tube by a valve, opening and closing 60 the communication between the tank and the tube; and to improve generally the construction, arrangement and operation of the several appliances entering into the formation 65 of the machine as a whole.

The invention consists in the features of construction and combinations of parts hereinafter described and claimed.

In the drawings illustrating the invention, Figure 1 is a side elevation of the machine 70 as a whole; Fig. 2 a top or plan view, showing the feed rollers and revoluble brushes, with the support for the carpet removed; Fig. 3 a longitudinal section through the machine with the valve operating means for 75 the valves of the vacuum tubes omitted; Fig. 4 a top or plan view of the supporting frame for the carpet with the feed rollers and revoluble brushes removed; Fig. 5 a cross section on line $a-a$ of Fig. 1; Fig. 6 a detail showing the upper end of a vacuum tube or pipe and valve-operating means; Fig. 7 a detail in longitudinal section of the parts shown in Fig. 6; Fig. 8 a detail in section showing the valve of the water tank with 80 operating means therefor; Fig. 9 a detail in elevation of the discharging tube or pipe for the water; Fig. 10 a detail in side elevation showing a modification in the carpet supporting rods; Fig. 11 a detail in side elevation, showing a brush and roller for supporting the carpet; Fig. 12 a cross section through the upper end of one of the pipes or tubes, showing the controlling valve with arms at each end for operating the same and 85 having the arms connected by a cross rod; Fig. 13 a side elevation of a portion of the driving gear for revolving the feed rollers and brushes, with the driving chains omitted; Fig. 14 a top or plan view of the parts 90 shown in Fig. 13, with the driving chains omitted; and Fig. 15 a top or plan view of the parts shown in Figs. 13 and 14, with the arrangement of driving chains employed for driving the rollers and brushes.

The construction shown has a frame consisting of longitudinal or side pieces 1 and cross or end pieces 2, united to the longitudinal or side pieces in any suitable manner; and the frame is supported by means of 105 110

legs or standards 3, at each corner of the side pieces, bolted to the side pieces and bolted or otherwise connected with a floor or base piece 4, so as to furnish a support 5 for the frame and the operating devices carried by the frame.

The frame, at its receiving end and discharge end for the carpet, has guide or presser rollers 5, journaled in suitable standards 6 attached to the side rails, and between which guide or presser rollers the carpet is fed forward over the frame. The frame has longitudinally thereof a plurality of feed and retention rollers 7, and each feed or retention roller 7 has, on its circumference, rubber 8, which acts to engage the nap of the carpet passing over the frame and advance or feed forward the carpet, under a slow speed thereof as compared with the speed of the revolving brushes, and each roller 7 is supported at each end in a suitable journal box or bearing 9 attached to the side rails of the frame, so that each roller is mounted so as to revolve freely. The frame 25 has extending longitudinally thereof a plurality of revoluble brushes 10, each brush having bristles of a sufficient stiffness to act on the carpet and separate and remove the dust and dirt from the carpet, as the carpet 30 advances in contact with the brushes. Each brush extends crosswise of the frame and is mounted in a suitable journal box or bearing 11 at each end, which journal boxes or bearings are supported on the side rails of the 35 frame. A plurality of longitudinal rods 12 extend from end to end of the frame, and these rods are supported by cross strips 13 attached to the side frames, so that the rods are in a plane parallel with the upper traveling surface of the rollers 7 and brushes 10, for the brushes to contact the under face of the carpet as the carpet is fed forward over the frame.

Each revolving brush 10 has coöperating therewith a flat tube or pipe consisting of an upper section or portion and a lower section or portion, the upper section or portion 14 of which is for suction and terminates, at its upper end in a trough 15 in which the brush lies, as shown in Fig. 3, by which arrangement the dirt and dust, separated and removed from the carpet by the action of the brush, will be drawn down into the upper pneumatic or suction section 14 of the 50 flat tube or pipe. The upper section 14 of each tube or pipe is of the full inside width of the frame, and the troughs 15 correspond in length with the length of the brush, so that the brush can lie within the ends of the 55 trough of its pneumatic or suction pipe. Each upper section of each flat tube or pipe, as shown, depends vertically from its mouth or trough 15, and the lower section 16 of the tube or pipe, which is for water, has a vertical straight portion and an inclined

straight portion, which is gradually narrowing until it terminates in a mouth or discharge end adapted to enter a receiver common to all of the pipes.

Each flat tube or pipe at the juncture of its upper and lower sections is in communication with a water supply tank 17, and, in the arrangement shown, each water supply tank 17 has one side wall formed by the wall of the tube or pipe and the other side wall formed by an inclined wall 18, and each supply tank for water is closed at each end by a wall or plate 19, so as to confine the water and have a free discharge for the water through the medium of the inclined 75 side wall 18, which tends to direct the flow of water from the tank downwardly into the upper end of the lower or water section of the tube or pipe. The construction shown has two tanks 17 located side by side, with 80 their inclined walls 18 coming to an apex, and water, as shown, is supplied to both tanks 17 by a supply pipe 20, having a perforated or slotted under side to allow the free escape of the water on each side of the 85 apex into the two supply tanks in equal amount. Each supply pipe 20 leads from a common feed pipe 21, and extends the full width of the flat suction and water tubes or 90 pipes. The feed pipe 21 is connected with a supply pipe 22, leading from a centrifugal or other type of force pump 23, which is driven or operated from an electric motor 24 or otherwise. Each water tank 17, at its 95 lower or contracted end, is in communication, with its lower section 16 of the pipe or tube by openings or passages 25, so that, when the openings or passages 25 are open water, can flow from the tank 17 into the lower or water section 16 of the pipe or 100 tube, creating a downward suction in the upper section 14 of the pipe, and its mouth or trough 15 from a point above the inlet for the water, which suction operates to draw down the separated and removed dust 105 and dirt. The lower sections 16 of the plurality of pipes or tubes, terminate in a common receptacle 26, so as to discharge the water and dirt and dust commingled therewith into the receptacle, and from the receptacle 26 the water, with the dust and dirt therein, is drawn into the pump 23, by means of a connecting pipe 27 for the water to be discharged from the pump through the pipe 22, thereby maintaining a continuous feed of the water to the chambers 115 17, and a continuous flow from the chambers 17 through the pipes or tubes, so long as the pump is operated.

It is desirable, in order to save power, that the creating of a suction in each flat tube or pipe should occur as the advanced end of the carpet reaches and passes over each succeeding rotary brush from the first to the last, and for this purpose each flat suction 120 130

pipe or tube, at its juncture with the bottom of the mouth or trough 15, has a flap or other valve located and operating to open and close communication between each flat suction pipe or tube and its mouth or trough 15, as the carpet, in its forward movement, reaches and passes over a brush. The arrangement shown has, for each suction pipe or tube, a valve 28, located at the juncture 5 of the pipe or tube with its mouth or trough, which valve 28 is supported on a rod 29 extending from end to end of the pipe or tube, and mounted in suitable bearings 30, so as to allow the valve to be raised and lowered as required to open the tube or pipe 15 for suction, or to close the pipe or tube against suction. The arrangement shown has, at each end of the rocking rod 29, a stuffing box 31 to prevent leakage in use, and 20 on each end of the rods an arm 32, connected by a pivot 33 with a link 34 of a lever 35, which is pivotally mounted on a cross rod 36 with the upper end of the lever 35 in a slightly higher plane than the upper travelling surface of the feed rollers 7 and rotary brushes 10, so that, as the advanced edge of the carpet strikes the upper end of the lever 35, the lower end of the lever will be moved forward, throwing down the crank 32 and 25 raising the valve 28 into the open position, as shown by the valve of the first flat pipe or tube in Fig. 3, thereby opening the flat tube or pipe for creating a suction by the flow of water through the lower section of 30 the flat tube or pipe, by which the dust and dirt, removed by the rotary brush, will be drawn down to commingle with the water. Each flat pipe or tube has a valve 28 with an operating crank and lever, so that, as the 35 forward edge of the carpet reaches and engages successively the upper end of each lever, the valves of the several pipes or tubes will be successively opened. Each valve 28 is thrown down to close its pipe or tube, in 40 the arrangement shown, by a coiled spring 37, one end of which is attached to the lever 35 and the other end of which is attached to a pin or stud 38 on the side rail, it being understood that each end of the rod for the 45 controlling valve 28 has a crank arm and a lever, with a spring or other means, for returning the lever and the valve to their closed positions.

The upper end of each lever 35 has an in- 50 turned portion 39 so as to insure a contact of sufficient extent to oscillate or vibrate the lever and open the valve; and if desired or necessary, the inturned portions 39 could be connected by a rod or bar 40, shown by 55 dotted lines in Fig. 7, so as to operate both levers 35 simultaneously.

The tanks 17 should be filled with water before allowing the water to flow from each tank into its pipe or tube; and for this purpose a valve should be provided to control 60

the openings or passages 25 between the tank and its tube or pipe. The arrangement shown has a gate or other valve 41, movable in end guideways 42 and intermediate guideways 43, so as to have a vertical movement 70 for opening and closing the passages 25 to shut off the outflow of water from the tank or allow the water to flow from the tank into its tube or pipe.

Each gate or other valve 41 is connected by rods 44 with a cross rod 45, and each cross rod 45 is connected to a vertically movable bar 46 at each end thereof, which bar is movable in guides 47, so as to be free to rise and fall, and thereby raise and lower 80 the gate or other valve. Each vertically movable bar 46 is connected with a plurality of links 48, each link attached to a stud or pivot 49 on the bar, and the opposite end of each link is attached by a pin or pivot 50 to a longitudinally sliding bar 51, held in guides or keepers 52, so that with the endwise movement of the longitudinal sliding bar 51 the links 48 will operate and raise the bar 46, and with it the gate or other valve, 85 and allow water to flow from a tank 17 into its pipe or tube. The construction shown has each endwise sliding bar 51 connected by a pivot 53, with a depending arm 54 which arms 54, are connected to a cross rod 55, supported in brackets 56 and having an arm 57 for the attachment of a cord or other device, by means of which the rod 55 can be rocked to swing the arms 54 and move the sliding bars 51 endwise; and, as shown, 90 the bars are returned to normal position by coiled springs 58, one for each arm 54, and connected at one end to the arm and at the other end to the outer tube, as shown in Fig. 1. 100

It is desirable, that the brushes shall have a higher speed than the feed rollers. As shown, the shaft of each feed and retaining roller has, on one end thereof, sprocket wheels 59 and 60, and the shaft of each rotary brush has on one end thereof, sprocket wheels 61 and 62, with the sprocket wheels 61 and 62 of a less diameter than the sprocket wheels 59 and 60, so as to give a 105 higher speed for the brushes. 110

The driving means shown consists of a sprocket chain 63 running around the driving sprocket wheel 59 on the shaft of the first roller 7 and a sprocket chain for the sprocket wheel 60 on the shaft of the first roller 7 and the sprocket wheel 62 on the first brush shaft, and another sprocket chain running around the sprocket wheel 61 on the shaft of the first brush, and the sprocket wheel 59 on the shaft of the second roller, 115 and another sprocket chain for the sprocket wheel 60 on the shaft of the second roller and the sprocket wheel 62 on the shaft of the second brush, and so on as shown by dotted lines in Fig. 2, so that the sprocket 120

chains will alternate from a large to a small sprocket wheel, and from a small to a large sprocket wheel, thereby giving a higher speed of rotation for the brushes than the speed of the feed rollers; but other driving means than sprocket chains and sprocket wheels can be used so long as the drive is one furnishing a higher speed for the rotary brushes than for the feed rollers.

10 The construction shown in Fig. 1 has a single series of guide rods 12 for supporting the carpet in position to pass over and in contact with the rotary brushes, but if desired or necessary, means for holding the carpet down can be provided. The holding of the carpet down can be attained by the use of a second series of guide rods 64 over the lower series 65, as shown in Fig. 10; and this second series of guide rods 64 have cross straps or bars 66, connected by tension springs 67 at each end of each cross bar or strap, which springs are attached to the side rails 1 of the frame, or otherwise connected, so as to act and allow the necessary yield for 25 the guide bars to permit the passage of the carpet between the upper and lower series of guide bars.

An arrangement of tension rollers 68 can also be employed for holding down the carpet as shown in Fig. 11. Each tension roller is supported so as to be yieldable by means of suitable springs 69, and a tension roller, in the arrangement shown, is located over each brush, and with this arrangement the 30 guide rods can be dispensed with, if so desired.

The operation will be understood from the foregoing description, but briefly is as follows: The carpet is entered between the receiving rollers 5, at the front of the machine, and is engaged by the feed rollers, and carried forward by the action of such rollers in connection with the rotary brushes. The tanks 17 are filled with water to the required 40 height, and when full, the valves controlling the communication between the lower or water section 16 of the pipes or tubes and their respective tanks 17, are opened, allowing water to flow from each discharge tank into its pipe or tube, and such flow of water through the pipe or tube will create a suction in the upper section 14 of the pipe or tube, the amount of suction, depending on the rapidity of the flow of the water and the 45 length of the suction pipe or tube between its upper end and the point of admission of the water to the pipe or tube. After suction has been established by the down flow of the water through the lower sections of the 50 pipes or tubes, as the forward edge of the carpet reaches the levers 35 of the first pipe or tube, the forward travel of the carpet will open the controlling valve of this pipe or tube so that the dust, separated and removed

by the rotation of the brush of this pipe or 65 tube, will be drawn down into the upper section 14 of the pipe or tube and commingled with the water in the lower section 16 of the pipe or tube. Each controlling valve of the several pipes or tubes will be successively 70 opened, as the forward edge of the carpet engages with the levers 35 of the controlling valve, so that each pipe or tube in succession will be opened for the removal of the dust and dirt separated from the carpet by the action of the rotary brush of each pipe or tube. The carpet travels the full length of the plurality of brushes, and its forward end, in the arrangement shown, passes under the rollers 5 at the rear end of the machine, 75 for removal of the carpet from the machine. The dust and dirt commingles with the water passing through each pipe or tube; and the water, with the dust and dirt commingled therewith, enters the common receiver 26 and is drawn through the pipe 27 into the pump 23, and returned through the lead pipe 22 to the feed pipes for the several tanks, so as to keep the tanks supplied 80 with water, and thereby maintain a continuous flow through the pipes or tubes for creating the requisite suction in the upper sections of the several pipes or tubes to remove the dust and dirt separated by the rotary brushes. After the water becomes too 85 foul for further use, it can be discharged from the pump and new water supplied to the tanks for receiving the dust and dirt. The carpet is to be passed over the rotary brushes once or a sufficient number of times 90 to thoroughly cleanse the carpet; and under the term carpet is included fabrics and materials of any description which can be cleaned by the brushes and suction.

What I claim as new and desire to secure by Letters Patent is:

1. In a pneumatic carpet cleaning machine, the combination of a supporting frame, a series of revoluble feed rollers, a series of rotary brushes, each brush traveling at a greater speed than the feed rollers, the rollers and brushes arranged parallel one with the other and having their upper traveling surfaces in the same horizontal plane, a downwardly leading flat pipe for 110 each brush and having the brush inclosed at its upper end, a fixed horizontal carpet support extending over and located in the plane of the upper traveling surfaces of the entire series of rollers and brushes, means for supplying a stream of water to flow downwardly in the pipe and create a suction in the upper portion of the pipe, the water receiving and removing the dust and dirt separated from the carpet by the action 115 of the brush, and a controlling valve for each pipe below each brush, each valve being provided with operating means by 120 125

which it is automatically operated with the forward travel of the carpet, substantially as described.

2. In a pneumatic carpet cleaning machine, the combination of a supporting frame, a plurality of revolving feed rollers, a plurality of rotary brushes, a suction pipe for each brush inclosing its brush at the upper end, means for creating a suction in said pipe, a controlling valve below the brush for each pipe, and means for automatically operating each controlling valve from the forward travel of the carpet, substantially as described.

3. In a pneumatic carpet cleaning machine, the combination of a supporting frame, a series of guide rods extending longitudinally of the frame and furnishing a horizontal support for the carpet, a plurality of revoluble feed rollers below the guide rods, a plurality of rotary brushes operating under the guide rods, the rollers and the brushes arranged parallel one with the other and spaced apart and having their upper traveling surfaces in the same horizontal plane, a downwardly leading flat pipe for each brush and having the brush inclosed within its upper end, a water supply tank for each pipe, and means for supplying water to each tank to be discharged into and flow downwardly through each flat pipe and create a suction in the pipe, the water receiving and removing the dust and dirt separated from the carpet by the action of the brush, substantially as described.

4. In a pneumatic carpet cleaning machine, the combination of a supporting frame, a series of guide rods extending longitudinally of the frame and furnishing a horizontal support for a carpet, a plurality of revoluble feed rollers below the guide rods, a plurality of rotary brushes

operating under the guide rods, with the feed rollers and brushes alternating and the brushes having a higher speed than the feed rollers, and with the rollers and brushes arranged parallel one with the other and spaced apart and having their upper traveling surfaces in the same horizontal plane, a suction pipe for each brush, the upper end of each pipe inclosing its brush, means for creating a suction in each pipe and a valve for each pipe at its upper end, and automatically operated from the forward travel of the carpet, substantially as described.

5. In a pneumatic carpet cleaning machine, the combination of a frame, a revoluble feed roller mounted on the frame, a rotary brush traveling at a greater speed than the feed roller and mounted on the frame in advance of the roller, with the roller and brush spaced apart and having their upper traveling surfaces in the same horizontal plane and arranged parallel one with the other, a downwardly leading flat pipe for the brush having the brush inclosed within its upper end and receiving thereinto and removing the dust and dirt separated from the carpet by the action of the brush, a fixed horizontal carpet support extending over and located in the plane of the upper traveling surfaces of the roller and brush, means for supplying a stream of water to flow downwardly in the pipe and create a suction in the upper portion thereof, a shut-off for the upper end of the pipe below the brush, and means for opening the shut-off to furnish communication between the brush and pipe as the carpet travels over the brush, substantially as described.
